UNITED STATES PATENT OFFICE

163,995

MILK CARTON HOLDER

Jack H. Firanzi, San Jose, Calif.

Application March 6, 1950, Serial No. 8,345

Term of patent 14 years

(Cl. D44—21)

To all whom it may concern:

Be it known that I, Jack H. Firanzi, a citizen of the United States, residing at San Jose, in the county of Santa Clara and State of California, have invented a new, original, and ornamental Design for a Milk Carton Holder, of which the following is a specification, reference being had to the accompanying drawing, forming a part thereof.

In the drawing:

Fig. 1 is a side elevational view of a milk carton holder showing my new design;
Fig. 2 is a top plan view thereof;
Fig. 3 is a front elevational view;
Fig. 4 is a rear elevational view; and

Fig. 5 is an elevational view taken in the direction of the arrow 5 in Fig. 2.

I claim:

The ornamental design for a milk carton holder as shown.

JACK H. FIRANZI.
